UNITED STATES PATENT OFFICE.

JOHANN MARTIN WETCKE, OF DUISBURG, GERMANY.

MOVABLE CHARGING DEVICE FOR A FURNACE.

1,205,690.

Specification of Letters Patent. Patented Nov. 21, 1916.

Application filed June 23, 1914. Serial No. 846,861.

To all whom it may concern:

Be it known that I, JOHANN MARTIN WETCKE, a subject of the King of Prussia, residing at 14 Kölnerstrasse, Duisburg, Germany, have invented certain new and useful Improvements in a Movable Charging Device for a Furnace; and I do hereby declare the following to be a full, clear, and exact description of the invention.

10 The object of the invention is to provide a new and improved charging device for placing the articles or materials, such as bar iron, pipes, sheet metal, ingots and the like to be heated and roasted into the furnace or oven and for allowing removal of the charging device from the interior of the furnace during the roasting of the material so that the charging device is not unduly subjected to the heat and hence a long 20 life is assured.

In order to accomplish the desired result, use is made of a charging device adapted to pass sidewise into and out of the oven or furnace.

25 A practical embodiment of the invention is represented in the accompanying drawings forming a part of this specification, in which similar characters of reference indicate corresponding parts in all the views.

30 Figure 1 is a cross section of the improved charging device in position within the oven or furnace; Fig. 2 is a longitudinal section of the same; and Fig. 3 is a diagrammatic plan view of the same.

35 The carriage A is provided with rolls B unsupported at one end. The rolls B can be raised and lowered a predetermined distance for instance by hydraulic or air cylinders E and turned forward or backward

40 by a suitable motor G mounted on the carriage or the like. The carriage A with the rolls B mounted thereon is movable sidewise on rails H so that the rolls B in one position of the carriage A are inside the 45 oven and extend throughout the width thereof, and in another position of the carriage A the rolls B are outside of the oven.

In the hearth of the oven are openings or recesses C for the reception of the rolls B 50 to allow the latter to enter while in lowermost position, as shown in Fig. 1. When the rolls are moved out of the oven the openings C can be closed by doors F.

55 For heavy materials or articles, use is made of bearings D for the reception of the outer free ends of the rolls B, the bearings

D being located at the side of the oven opposite the one having the entrance for the rolls B. The bearings D are adapted to be raised or lowered with the rolls B for 60 instance by separate cylinders I.

In front only or in the front and in the rear of the oven are located sets of rolls K and L which when in raised position are flush with the top of the rolls B of the carriage A.

The operation is as follows: The article or material to be heated or roasted such as bar iron or the like is first placed on the rolls in front of the oven. Then the movable charging device is moved sidewise from its outermost position into the interior of the oven and then raised until the rolls B are flush with the front set of rolls supporting the articles or materials. The two sets 75 of rolls are now turned so that the articles or materials are moved forward until the position for heating is reached. The rotation of the rolls is now stopped and the rolls B are lowered and moved out of the 80 oven by moving the carriage away from the side of the oven. The operation takes but a short time so that the rolls B while within the oven are not unduly affected by the heat therein. After the heating or 85 roasting is completed the carriage A and rolls B are returned and raised to lift the articles and materials off the hearth, and then the rolls are rotated to transfer the articles or materials either to the set of 90 rolls at the front of the oven, or onto the set of rolls at the rear of the oven, as desired, the rolls B and the front or rear sets of rolls being turned in the corresponding direction.

95 I claim as my invention:

1. A furnace provided with side openings, a carriage adapted to be raised and lowered, rolls mounted on the said carriage and adapted to be turned, and a track for the carriage extending at a right angle to one side of the furnace to allow of moving the carriage sidewise to pass the rolls into or out of the furnace.

2. A furnace provided with side openings, 105 a carriage adapted to be raised and lowered, rolls mounted on the said carriage and adapted to be turned, a track for the carriage extending at a right angle to one side of the furnace to allow of moving the carriage sidewise to pass the rolls into or out of the furnace, and delivery and removing 110

end rolls in the end of the furnace for passing the material onto the set of rolls or from the latter onto the end rolls.

3. A furnace provided with a front opening for the introduction of the material to be heated, the furnace having side openings, a carriage movable toward and from the side openings of the said furnace, rolls mounted on the carriage and projecting therefrom, the rolls being adapted to pass into and out of the furnace through the side openings, the rolls when within the furnace extending transversely of the same to receive and support the material introduced through the front of the furnace, and means for turning the said rolls to cause the same to carry the material to heating position.

4. A furnace provided with a front opening and side openings, a charging device provided with rolls adapted to be moved into and out of the furnace through said side openings, and means at the front of the furnace for supporting the materials to be heated and directing the same through the

front opening onto the rolls of the charging device when the latter are within the furnace.

5. A furnace provided with a front opening and side openings, a charging device provided with rolls, means for raising and lowering the charging device and its rolls, the rolls of the charging device when in lowered position being adapted to be moved into and out of the furnace through said side openings, rolls arranged at the front of the furnace for supporting the material and passing the same onto the rolls of the charging device when the latter are in raised position within the furnace, and means for turning the rolls of the charging device.

In testimony whereof I have signed my name to this specification in the presence of two subscribing witnesses.

JOHANN MARTIN WETCKE. [L. S.]
